UNITED STATES PATENT OFFICE

99,979

DESIGN FOR A STATUETTE OR SIMILAR ARTICLE

Sigmund Lee Wolffs, Chicago, Ill.

Application April 17, 1936, Serial No. 62,177

Term of patent 7 years

To all whom it may concern:

Be it known that I, Sigmund Lee Wolffs, a citizen of the United States, residing at Chicago, Cook County, Illinois, have invented a new, original, and ornamental Design for a Statuette or Similar Article, of which the following is a specification, reference being had to the accompanying drawing forming a part thereof.

Figure 1 is an elevational view showing one side of the statuette or similar article embodying my new design.

side of the statuette or similar article embodying my new design.

Figure 3 is an elevational view showing the side of the statuette or similar article embodying my new design opposite to that shown in Figure 1.

Figure 4 is an elevational view showing the front of the statuette or similar article embodying my new design.

I claim:

The ornamental design for a statuette or similar article as shown and described.

SIGMUND LEE WOLFFS.
